CLAIM

The ornamental design for hot stove for blast furnace, as shown and described.

DESCRIPTION

FIG. 1 is a front perspective view of hot stove for blast furnace in accordance with the new design;

FIG. 2 is a front view thereof;

FIG. 3 is a top view thereof; and,

FIG. 4 is a bottom view thereof.

The broken lines shown are included for the purposes of illustrating portions of the hot stove for blast furnace that form no part of the claim.
